(No Model.)

J. GIFFORD.
SNOW SHOVEL.

No. 606,534.

Patented June 28, 1898.

UNITED STATES PATENT OFFICE.

JOHN GIFFORD, OF WATERTOWN, NEW YORK.

SNOW-SHOVEL.

SPECIFICATION forming part of Letters Patent No. 606,534, dated June 28, 1898.

Application filed August 9, 1897. Serial No. 647,628. (No model.)

To all whom it may concern:

Be it known that I, JOHN GIFFORD, a citizen of the United States, residing at Watertown, in the county of Jefferson and State of New York, have invented a new and useful Snow-Shovel, of which the following is a specification.

This invention relates to snow-shovels, its object being to provide a device of this character comprising a sheet-metal blade secured to and supported by a suitable frame, formed, preferably, of wood and wire, a wooden handle secured to the blade, and an auxiliary hand-grip adjustably supported on the handle.

With these objects in view the invention consists of the several details of construction and combination of parts, as will be herein-after fully described, and particularly pointed out in the claims.

In the drawings, Figure 1 is a perspective view of a snow-shovel made in accordance with my invention. Fig. 2 is a bottom plan view of the shovel, a portion of the blade and the handle being broken away. Fig. 3 is a section on the line xx of Fig. 2 inverted. Fig. 4 is a side elevation of a portion of the handle and the auxiliary hand-grip on an enlarged scale. Fig. 5 is a vertical longitudinal section of Fig. 4, showing the hand-grip folded down.

Similar reference-numerals indicate similar parts in the several figures.

In carrying out my invention I provide a supporting-frame for the blade, comprising three parallel bars of wood, indicated, respectively, by the numerals 1, 2, and 3, connected at their ends by the side wires 4. These wires will preferably be secured to the bars by clips 5, although they may be secured to them in any other suitable manner. The wires are curved and the wooden strips are of unequal length in order to give the blade the proper conformation, and the front edge of the forward bar 1 is beveled, as indicated at 6.

7 indicates a sheet of metal, preferably galvanized steel, fitted over the upper face of the frame, and the front or lower portion of this sheet is folded over the lower face of the front bar 1 and also over its rear edge and is soldered to the main portion of the sheet, as indicated at 9. The side edge portions 10 are also folded over upon the wires 4 and the ends

of the wooden bars, and the upper or rear edge portion 11 is folded over upon the rear bar 3 and preferably secured in place by a series of rivets 12.

13 indicates a loop formed of a strip of metal bent upon itself and fitted over the front edge of the metal sheet 7, and this loop forms a shoe for the tapering front end abutting 60 against the rear edge of the bar 1 of the handle 14, said end fitting between the under face of the metal sheet 7 and the lower member of the loop and being secured in place by a series of rivets 15, which pass through the 65 sheet 7, the handle, and both members of the loop 13.

16 indicates a strip, preferably of hardened steel, which is firmly secured to the lower face of the metal sheet 7 by a series of rivets, and projects forwardly beyond said sheet and has its front edge beveled, as indicated at 18. In order to prevent any abrupt shoulder, solder may be run on the upper face of the strip 16, immediately in front of the folded 75 edge of the metal sheet 7, as indicated at 20.

The handle 14 is curved at its forward end to correspond to the contour of the blade and is provided with a recess 19 to receive the middle bar 2. The handle is firmly secured to 80 the blade by a series of rivets or other similar suitable securing devices. The upper or rear end of the handle is split to form a fork 21, between the members of which the hand-grip 22 is secured in the usual manner.

23 indicates a strip of wood secured on the upper face of the blade at its rear edge by rivets 24 or other similar fastening devices.

25 indicates the auxiliary hand-grip, which is secured between the outer ends of spaced 90 arms 26 of a supporting-frame, which is formed from a strip of metal bent to form the rectangular U-shaped portion 27, from which the arms 26 are curved outwardly and upwardly.

28 indicates a U-shaped slide to fit snugly 95 on the handle, the arms 29 of which project above the upper face of the handle, and between these arms the U-shaped portion 27 of the hand-grip frame is eccentrically pivoted on a pin 30, the said pin being secured in said 100 arms 29 near their front edges. The arms 29 are provided with slots 31 in their rear edges, and the U-shaped part 27 of the hand-grip frame is provided with similar slots 32 in its

rear edges, and when the hand-grip frame is in a vertical position the slots 31 and 32 will register.

- Between the lower face of the **U**-shaped part 27 of the hand-grip frame and the upper face of the handle a spring 33 is loosely fitted, the said spring being formed from a strip of spring metal bent to give it the desired form. The spring 33 comprises the straight portion 34, the upwardly-disposed loop 35, the straight portion 36, which is parallel to the straight portion 34, and the loop 37, which is vertically disposed and substantially parallel to the loop 35.
- 15 39 indicates a pin which is in the loop 37. The **U**-shaped part 27 of the hand-grip frame is supported by the straight part 36 of the spring between the loops 35 and 37, and when the hand-grip frame is in a vertical position the spring 33 can be pushed forwardly below it until the pin 39 engages in the registering slots 31 and 32, when the hand-grip will be locked in its vertical position. By moving the spring rearwardly to disengage 25 the pin 39 from the slots 31 and 32 the hand-grip can be folded down, as indicated in Fig. 4. As the hand-grip is pivoted in advance of its vertical center, it is obvious that when it is gripped to lift the blade it will naturally swing to the rear and the **U**-shaped portion of the hand-grip frame will bear at its rear edge upon the spring 33 and force it down into close contact with the handle, and the downwardly-curved end 34 of the spring 30 will bite into the handle and prevent the hand-grip from slipping rearwardly on the handle. The hand-grip can be easily and quickly adjusted to any part of the handle to bring it in proper position for use with either 35 a heavy or light weight on the shovel-blade.

40 From the foregoing description it will be seen that I have produced an exceedingly strong and at the same time light-weight shovel, for it is obvious that the sheet metal 45 7 can be very thin and that the wooden bars and the side wires will form a strong and rigid support for the sheet metal, and by bending over the edge portions in order to secure the sheet to the frame the edges will 50 be stiffened and the blade will be rendered very strong and durable.

55 It is well known that in snow-shovels almost the entire wear comes upon the front edge of the shovel, and by providing the strip of hardened metal at the front edge and protecting the front end of the handle with the metal loop 13 this wear will be amply provided for, and it is obvious that when either the strip of hardened metal or the loop 13 becomes 60 worn out they can be easily replaced.

65 Instead of using wires to connect the ends of the parallel wooden bars it is obvious that strips of wood might be employed with good results; but I prefer to use the wires, since they afford the necessary strength without being cumbersome or bulky.

It will be understood that changes in the

form, proportion, and the minor details of construction may be resorted to without departing from the spirit or sacrificing any of the 70 advantages of this invention.

Having thus described the invention, what I claim is—

1. In a snow-shovel, a blade comprising a frame composed of a series of parallel wooden bars connected at their ends by side rods, and a metal sheet secured upon said frame, substantially as described. 75

2. In a snow-shovel, a blade comprising a frame composed of a series of parallel wooden bars connected at their ends by side rods, and a metal sheet having its edge portions folded over upon said bars and side rods, substantially as described. 80

3. In a snow-shovel, a blade comprising a frame composed of a series of parallel wooden bars connected at their ends by side bars, a metal sheet having its edge portions folded over upon said bars and side rods, and a strip of hardened metal secured to the front edge 90 of the metal sheet, substantially as described. 85

4. In a snow-shovel, a blade comprising a frame composed of a series of parallel wooden bars connected at their ends by side rods, and a metal sheet secured upon the upper face of 95 said frame, combined with a handle secured to the lower face of the frame substantially midway its width, and a metal loop fitted over the front edge of the blade and the front end of the handle and secured thereto, substantially as described. 100

5. In a snow-shovel, a blade comprising a frame composed of a series of parallel wooden bars connected at their ends by side rods, and a metal sheet secured upon the upper face of 105 said frame, combined with a handle abutting at its front end against the rear edge of the front bar of the frame, and secured to the lower faces of the other bars, and a metal loop fitted over the front edge of the blade 110 and the front end of the handle and secured thereto, substantially as described. 115

6. In a snow-shovel, the combination with the handle, of a **U**-shaped slide fitted upon the handle, a hand-grip frame eccentrically pivoted between the arms of the slide, and a spring loosely fitted between the lower face of said frame and the upper face of the handle, substantially as and for the purpose specified. 120

7. In a snow-shovel, the combination with the handle, of a **U**-shaped slide fitted upon the handle, a hand-grip frame having a **U**-shaped portion eccentrically pivoted between the arms of said slide, a spring loosely fitted 125 between the said **U**-shaped part of the frame and the handle, said spring having a downwardly-curved portion to bite the handle when the hand-grip frame is rocked rearwardly upon it, substantially as and for the purpose 130 specified.

8. In a snow-shovel, the combination with the handle, of a **U**-shaped slide fitted upon the handle, a hand-grip frame having a **U**-

shaped portion eccentrically pivoted between the arms of said slide, the arms of said slide and **U**-shaped part of the frame having slots in their rear edges adapted to register when the said frame is in a vertical position, a spring loosely fitted between the said **U**-shaped part of the frame and the handle, said spring comprising a horizontally-disposed portion to slide on the handle, and two spaced vertically-disposed loops between which the hand-grip frame is supported, and a pin se-

cured in the rear vertical loop to engage in said slots when they register, substantially as described.

In testimony that I claim the foregoing as my own I have hereto affixed my signature in the presence of two witnesses.

JOHN GIFFORD.
